(57) **CLAIM**

The ornamental design for a joint connector for automobile battery charging cord, as shown and described.

DESCRIPTION

FIG. 1 is a perspective view of a joint connector for automobile battery charging cord showing my design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.
